UNITED STATES PATENT OFFICE.

FRANK C. GIBSON, OF BALLSTON, VIRGINIA.

TIRE-BOLT WRENCH.

SPECIFICATION forming part of Letters Patent No. 762,049, dated June 7, 1904.

Application filed March 28, 1904. Serial No. 200,376. (No model.)

To all whom it may concern:

Be it known that I, FRANK C. GIBSON, residing at Ballston, in the county of Alexandria and State of Virginia, have invented a new and Improved Tire-Bolt Wrench, of which the following is a specification.

My invention relates to an improved tire-bolt wrench designed to provide a simple and practical tool for quickly and conveniently removing nuts from bolts or applying nuts to bolts without danger to the felly and to provide means for holding a plurality of nuts to be screwed onto alternate bolts.

With other objects in view, which will be hereinafter apparent, the invention consists in certain novel constructions and combinations of parts, all of which will be first described in detail and then specifically pointed out in the appended claims.

The bolts which fasten the tires to fellys of vehicle-wheels are usually constructed with round countersunk heads which have no niche in them, and after the tire has become worn and is required to be renewed there is great difficulty in removing the bolts, owing to the fact that the effort to turn off the nut on the inside of the felly by an ordinary wrench causes the entire bolt to swivel and turn inside the felly and tire, so that the nut cannot be turned over the threads of the bolt. This is so by reason of the fact that there is no niche in the head of the bolt to receive a screw-driver with which to hold the bolt while turning off the nut, and even if there was it would become obliterated or worn off by the wear of the tire. This difficulty is further exaggerated by the fact that the nut and bolt from constant wetting become rusted together, so as to render the starting of the nut on the bolt

more difficult. The result is that in many cases the end of the bolt carrying the nut has to be cut off with a cold chisel and at the expense of much time and tedious labor and the scarifying of the felly. Again, in applying nuts to bolts in the assembling of the wheel the same objection to turning of the bolt is present, and hence I have designed my invention to operate to accomplish the results desired and avoid the difficulties just enumerated.

Referring now to the accompanying drawings, Figure 1 is a perspective view showing my invention applied for use. Fig. 2 is a longitudinal section thereof. Fig. 3 is a cross-section on the line 3 3 of Fig. 2. Fig. 4 is a 55 similar view on the line 4 4 of Fig. 2. Fig. 5 is a detail perspective view of the nut-holding magazine. Fig. 6 is a detail end elevation of my invention. Fig. 7 is a detail perspective view of the clutch-bar detached. 60

Referring now to the accompanying drawings, in which like numerals and letters of reference indicate like parts in all the figures, 1 designates a handle member, at one end of which is formed a U-shaped yoke or straddling member 2, whose free end terminates in ears 2^a for the purposes presently explained, and where the end 2^b and the enlarged portion 1^a of the handle member 1 join the said handle is provided with a bore 1^b and a slotted portion 1^c, as shown. The portion 1^a of the handle has shoulders 1^d 1^e to coöperate with the shoulder 3^a of the lever, fulcrumed, as at 2^b, with its end 3^c in the slotted portion 1^c of the enlarged portion 1^a of the handle, and the 70 said portion 1^a has a bridge-piece 1^f for the lever 3 to rest on when gripped by the hand of the operator and to hold the said lever parallel to the handle 1. 75

Held for longitudinal movement in the bore 80 1^b is a clutch-bar 4, having a pronged end 4^a and a rack-face 4^b, with which face the pawl 3^d, fulcrumed at 3^e in a cut-away portion 3^f of the lever, coöperates. The bar 4 has an elongated groove 4^e in its under face, in which 85 the end 5^a of the set-screw 5, held in the threaded aperture 5^b of the handle 1, projects to limit the movement of the said bar in its longitudinal direction.

Welded or otherwise secured to the ears 2^a 90c of the member 2 is a bearing member 6, having a flange 6^a and an annular bore 6^b, in which seats the annular hub 7^a of the wrench 7, which includes an annular disk 7^b of greater diameter than that of the hub 7^a. The disk 7^b has 95 its peripheral face provided with rack-teeth 7^c for the purpose presently to appear. The hub 7^a is so mounted in the bore 7^b that it will be free to turn on its longitudinal axis and is provided with an annular groove 7^d to 100

coöperate with the end 8^a of the screw-lug 8, held in the threaded aperture 6^c of the bearing member 6, the screw 7^a and the lug 8 serving to prevent the head 7 leaving the bore 6^b.

9 designates a ratchet-arm having a handle 9^a and an enlarged end 9^b, apertured, as at 9^b, to receive the flange 6^a of the member 6, whereon it has free movement in the arc of a circle perpendicular to the axial line of the bore 6^b of the member 6. Upon the arm 9 a Y-shaped latch 10 is fulcrumed, as at 10^a, to allow one of its arms 10^b to engage the rack-teeth 7^c to cause the wrench 7 to rotate with the arm 9.

The wrench 7 has a square and tapering bore 7^a to receive the magazine 11. (Shown in detail in Fig. 5, by reference to which and to Fig. 2 it will be seen the magazine 11 is of elongated shape and adapted to contain several nuts of one size, its outer end being formed with a bridge or closure piece 11^a, to which the coil-spring 12 is attached, and which coil-spring 12 forces the nuts 13 toward the inner or open end of the magazine.) The sides of the magazine 11 are slotted to form spring portions 11^b 11^c, having nibs 11^c at the ends to retard or check the premature exit of the nuts from the magazine, but which are so arranged as to readily allow the nuts to pass out of the magazine during the operation of securing them to the bolt 14. By providing different sizes of magazines different sized nuts may be removed or secured to the bolts by simply introducing in place of the one magazine other magazines of a different size.

From the foregoing it will be seen that when the operator desires to apply a nut to the bolt 14, passing through the wheel-felly 15 and tire 16, he places the wheel in a horizontal position and adjusts the implement, as shown in Fig. 1, with the bar 4 against the bolt-head 14^a and the wrench 7 against the nut end of the felly. The parts are tightly held in such position by reason of the lever 3 and its pawl connections with the rack-face 4^b of the bar 4. After the parts are in such position it is only necessary to operate the arm 9 to impart rotary motion to the wrench 7 and screw the nut onto the bolt. To remove the nuts from the bolts, it is only necessary to reverse the direction of rotation of the wrench 7, which is done by simply reversing the latch 10, as shown in dotted lines in Fig. 6.

When used exclusively to remove nuts from the wheel, an empty magazine is preferably placed in the wrench 7, so that several nuts may be received thereby.

By providing the U-shaped member and the adjustable bar 4 the implement may be used on wheels of a variety of sizes without changing the correlative arrangement of the members 6 and 1^a, and by providing a magazine 65 nuts of different sizes can be readily applied

or removed whenever desired by simply changing the magazine from one size to another.

From the foregoing description, taken in connection with the accompanying drawings, it is thought the advantages, construction, and complete operation of my invention will be readily understood by those skilled in the art to which it appertains.

I desire it understood that slight changes may be made without departing from the scope of the appended claims and the invention.

Having thus described my invention, what I claim, and desire to secure by Letters Patent, is—

1. A tire-bolt wrench, comprising a handle, a yoke and nut-receiving members, said handle having an aperture, a rack-bar slidable in said aperture toward the nut-receiving member, means for moving said bar in one direction in said aperture, and means for imparting rotary motion to the nut-receiving member, for the purposes specified.

2. A tire-bolt wrench comprising a handle, yoke and nut-receiving members, said handle having an aperture, a rack-bar movable in said aperture toward the nut-receiving member, means for moving said bar toward the nut-receiving member, and means for imparting rotary motion to the nut-receiving member.

3. In a tool of the character described, a handle portion having an apertured enlargement at one end, a clutch-bar having a rack-face mounted in said handle-aperture, a lever fulcrumed in said enlargement and extending parallel to said handle portion, a pawl carried by said lever for coöoperating with the bar-rack, a bridge portion joining with said enlargement, a bearing member having a bore secured to the yoke, a wrench member having a squared bore and a hub, mounted to turn in said bearing-bore, and means for rotating said wrench member.

4. In a tool of the character described, a handle portion having an apertured enlargement at one end, a clutch-bar having a rack-face mounted in said handle-aperture, a lever fulcrumed in said enlargement and extending parallel to said handle portion, a pawl carried by said lever for coöoperating with the bar-rack, a bridge portion joining with said enlargement, a bearing member having a bore secured to the yoke, with its bore in alignment with the bar, a wrench having a squared bore and a hub, mounted to turn in said bearing-bore, and means for rotating said wrench member.

5. In a tool of the character described, a handle portion having an apertured enlargement at one end, a clutch-bar having a rack-face mounted in said handle-aperture, a lever fulcrumed in said enlargement and extending parallel to said handle portion, a pawl carried by said lever for coöoperating with the bar-

- rack, a bridge portion joining with said enlargement, a bearing member having a bore secured to the yoke, with its bore in alignment with the bar, a wrench having a squared bore and a hub mounted to turn in said bearing-bore, means for rotating said wrench member, and a stop carried by said bearing member to prevent lateral movement of the wrench.
6. In a tool of the character described, a handle portion having an apertured enlargement at one end, a clutch-bar having a rack-face mounted in said handle-aperture, a lever fulcrumed in said enlargement and extending parallel in said handle portion, a pawl carried by said lever for coöperating with the bar-rack, a bridge portion joining with said enlargement, a bearing member having a bore secured to the yoke, with its bore in alignment with the bar, a wrench having a squared bore and a hub mounted to turn in said bearing-bore, means for rotating said wrench member, and a stop carried by said bearing member to prevent lateral movement of the wrench, and a stop carried by said handle enlargement to limit the longitudinal movement of the bar.
7. In a tire-bolt wrench, a handle portion having an apertured enlargement at one end, a clutch-bar having a rack-face and mounted in said enlargement-aperture, a lever fulcrumed to said enlargement and extending parallel to said handle portion, a pawl carried by said lever for engaging said rack-face, a U-shaped yoke secured at one end to the enlargement, a bearing member secured to the other end of the yoke, said bearing member having a bore concentric with the axial line of the bar, a wrench having a hub and a rack-disk mounted in said bearing member, an arm having an apertured enlarged end mounted on said hub, a pawl carried by said arm and engaging said rack-disk.
8. In a tire-bolt wrench, a handle portion having an apertured enlargement at one end, a clutch-bar having a rack-face and mounted in said enlargement-aperture, a lever fulcrumed to said enlargement and extending parallel to said handle portion, a pawl carried by said lever for engaging said rack-face, a U-shaped yoke secured at one end to the enlargement, said bearing member having a bore concentric with the axial line of the bar, a wrench having a hub and a rack-disk mounted in said bearing member, an arm having an apertured enlarged end mounted on said hub, a pawl carried by said arm and engaging said rack-disk, said hub having a peripheral groove, a lug carried by the bearing member for entering the said groove to prevent axial displacement of the wrench.
9. In a tire-bolt wrench, a handle portion having an apertured enlargement at one end, a clutch-bar having a rack-face and mounted in said enlargement-aperture, a lever fulcrumed to said enlargement and extending parallel to

to said enlargement and extending parallel to said handle portion, a pawl carried by said lever for engaging said rack-face, a U-shaped yoke secured at one end to the enlargement, said bearing member having a bore concentric with the axial line of the bar, a wrench having a hub and a rack-disk mounted in said bearing member, an arm having an apertured enlarged end mounted on said hub, a pawl carried by said arm and engaging said rack-disk, said hub having a peripheral groove, a rack carried by the bearing member for entering the said groove to prevent axial displacement of the wrench, and means for limiting the longitudinal movement of the bar.

10. In a tire-bolt wrench, a handle portion having an apertured enlargement at one end, a clutch-bar having a rack-face and mounted in said enlargement-aperture, a lever fulcrumed to said enlargement and extending parallel to said handle portion, a pawl carried by said lever for engaging said rack-face, a U-shaped yoke secured at one end to the enlargement, said bearing member having a bore concentric with the axial line of the bar, a wrench having a hub and a rack-disk mounted in said bearing member, an arm having an apertured enlarged end mounted on said hub, a pawl carried by said arm and engaging said rack-disk, said hub having a peripheral groove, a lug carried by the bearing member for entering the said groove to prevent axial displacement of the wrench, means for limiting the longitudinal movement of the bar, said means including a groove in the bar, and a lug carried by the handle for coöperating therewith.

11. In combination with a tire-bolt wrench including a handle member, a bolt-engaging clutch-bar, a yoke and a wrench member, said wrench member having a squared bore, of a nut-carrying magazine removably mounted in said bore, said magazine comprising a tubular member having an open end and adapted to receive a plurality of nuts, means for preventing the premature removal of the nuts, said means including a spring member having nibs.

12. In combination with a tire-bolt wrench including a handle member, a bolt-engaging clutch-bar, a yoke and a wrench member, said wrench member having a squared bore, of a nut-carrying magazine removably mounted in said bore, said magazine comprising a tubular member having an open end and adapted to receive a plurality of nuts, means for preventing the premature removal of the nuts, said means including a spring member having nibs, and means for normally forcing said nuts toward the open end of the magazine, for the purposes specified.

FRANK C. GIBSON.
